UNITED STATES PATENT OFFICE.

FRANK McDONALD, OF ROARING SPRING, PENNSYLVANIA.

CATHODE FOR ELECTROLYTIC CELLS.

1,167,705.

Specification of Letters Patent. Patented Jan. 11, 1916.

Application filed August 5, 1915. Serial No. 43,862.

To all whom it may concern:

Be it known that I, FRANK McDONALD, a citizen of the United States, residing at Roaring Spring, in the county of Blair and State of Pennsylvania, have invented certain new and useful Improvements in Cathodes for Electrolytic Cells; and I do declare the following to be a full, clear, and exact description of the invention, such as will enable others skilled in the art to which it appertains to make and use the same.

This invention relates to improvements in cathodes for electrolytic cells and more particularly to cells of the diaphragm type.

The object of the invention is to provide a cathode for electrolytic cells of the diaphragm type which is free from the objectionable features of metallic cathodes.

It is well known that all the commercial grades of salt contain varying amounts of alkaline earths particularly those of calcium and magnesium and when a solution of sodium chlorid is decomposed by the action of the electrical current in a cell of the diaphragm type for the commercial production of caustic soda and chlorin gas, the chlorin gas is set free at the anode and the sodium at the cathode where it immediately reacts upon the water contained in the cathode chamber, forming caustic soda. Concurrently with this operation any insoluble salts of calcium or magnesium which might be contained in the brine, as impurities, is deposited on the metallic cathode and as this deposit is a non-conductor of electricity it gradually increases the internal resistance of the cell, thereby necessitating an increase of power required to operate the cell. This deposit also closes the perforations in the metallic cathodes and these perforations are necessary to permit the diffusion of the caustic soda into the cathode chamber. Consequently the closing of these perforations lowers the current efficiency of the cell.

This invention is devised to overcome these objectionable features of metallic cathodes and consists in forming a cathode of carbonaceous material which while being a good electrical conductor is not affected by the products of electrolysis and to which the alkaline earths do not adhere, said earths remaining in a free condition indefinitely when such a cathode is employed.

With this and other objects in view the invention consists of certain novel features of construction and the combination and ar-

rangement of parts as will be hereinafter more fully described and claimed.

In the accompanying drawings: Figure 1 represents a longitudinal section through an electrolytic cell equipped with this improved cathode; Fig. 2 is a plan view thereof; Fig. 3 is a longitudinal section taken on the line 3—3 of Fig. 2; Fig. 4 is a transverse section taken on the line 4—4 of Fig. 2.

In the embodiment illustrated this improved cathode is shown applied to an electrolytic cell of the vertical diaphragm type employed for the electrolysis of sodium chlorid in the form of an aqueous solution or brine. As shown this cell comprises a containing tank or receptacle 1 composed of iron or other suitable metal provided with a cement lining 2. This tank 1 is equipped with an overflow pipe 3 for maintaining a constant electrolyte level in the cathode compartment of the tank, said pipe being shown extending through one side wall of the tank (see Fig. 2). Disposed within the tank 1 are the cathodes 4 which are preferably composed of graphite or other suitable carbonaceous material adapted for the purpose and are connected at their upper ends by a negative bus bar 5 which is secured thereto by connecting bolts 6. Suitable non-conductive gaskets 7 preferably composed of asbestos are shown arranged between the plates 4 (see Fig. 3) and the upper ends of these plates are rabbeted as shown at 8 the reduced portions 9 of which project above the caustic solution carried by the tank. The cathode plates which form the chambers 10 in the tank are spaced a suitable distance from the side walls of the tank and a cement bottom 11 projects upwardly between the plates 4 at opposite sides of the tank and holds them in spaced relation, said graphite plates being secured to said bottom by means of rods 12 which extend transversely through said bottom and through the plates at opposite sides thereof (see Fig. 4). The upper ends of these plates which are rabbeted as shown at 8 provide for the mounting thereon of a suitable cover 13 which may be composed of any acid-proof material preferably slate. This cover 13 is formed with a plurality of centrally arranged longitudinally aligned openings 14 to receive the leading in rods 15 attached to the upper ends of the anodes 16 the lower ends of which are mounted on the cement bottom 11 which spaces the cathode plates apart and forms

the bottom of the anode chamber. The ends of the anode chamber are closed by upright plates 26 which may be of glass, rubber or other suitable non-conducting material and which extend above the tank 1 and are provided on their inner faces with laterally extending flanges 27 to form seats for the ends of the cover member 13. A glass funnel 17 has the stem or shank 18 thereof inserted through an aperture in the cover 13 and extends into the anode chamber whereby the brine or other electrolyte may be conveniently poured into said anode chamber. The leading in rods 15 of the anodes 16 are connected at their upper ends above the top 13 by a positive bus bar 19. The negative bus bar with which the cathodes are connected and the positive bus bar 19 connected with the anodes serve to properly place the anodes and cathodes in circuit.

The portions of the cathode plates below the rabbets 8 therein which are designed to be submerged in the caustic solution are made porous by means of saw-cuts 20 to provide for the diffusion of the caustic solution in the cathode chamber. Arranged adjacent the sides of the cathode plates which are disposed next to the anodes is the porous diaphragm 21 which is preferably composed of sheets of asbestos having their upper edges bent laterally outward at right angles to form flanges 22 which are designed to rest on the rabbeted portions 8 of the cathode plates and be clamped thereon by the lower or inner edge of the cover 13 for the anode chamber.

While the cathode plates are shown arranged vertically in the cell it is supposed to be understood that they need not be necessarily so arranged but may be placed in an inclined or horizontal position without in any way departing from the scope of the invention.

Having fully set forth the structural details of the invention the operation thereof is as follows: The anode compartment having been filled with brine until the highest level thereof is attained, the funnel 17 being used for this purpose, the cathode compartment is filled with a caustic solution, its level be-

ing maintained constant by the overflow pipe 3. When the cell thus equipped is placed in an electric circuit the current will flow from the positive wire 24 to bus bar 19, from the latter to the anodes 16 through the electrolyte in the anode chamber to and through the porous diaphragm 21 to the graphite cathodes 4, through bus bar to the negative wire 24'. This current owing to the fact that the chlorin is an electro-negative element causes an evolution of the latter at the anodes 16 where it collects in the chamber formed above the electrolyte and from whence it is conveyed through a pipe 25 to any desired point. The sodium element being electro-positive is deposited at the negative pole or cathode and is liberated in the form of sodium and the sodium thus liberated reacts with the water to form caustic soda and free hydrogen gas.

It is of course to be understood that in practice as many of the alternate compartments of anodes and cathodes as may be desired may be built up together and that various changes in the form, proportion and the minor details of construction may be resorted to without departing from the principle or sacrificing any of the advantages of the claimed invention.

I claim as my invention:

1. A cathode for an electrolytic cell composed of a graphite plate having its upper end rabbeted and the portion thereof below said rabbet provided with transversely extending slots.

2. A cathode for an electrolytic cell composed of a graphite plate having its upper end rabbeted and the portion thereof below said rabbet provided with transversely extending slots, a bus bar connecting the reduced upper ends of said cathodes, and insulating gaskets arranged between the graphite plates.

In testimony whereof I have hereunto set my hand in presence of two subscribing witnesses.

FRANK McDONALD.
